UNITED STATES PATENT OFFICE.

LOUIS MARX, OF BROOKLYN, NEW YORK.

DESIGN FOR A CIRCUS TOY.

Application filed May 15, 1925. Serial No. 13,457. Term of patent 14 years.

To all whom it may concern:

Be it known that I, LOUIS MARX, a citizen of the United States, residing in Brooklyn, county of Kings, State of New York, have invented a new, original, and ornamental Design for a Circus Toy, of which the following is a specification, reference being

had to the accompanying drawing, forming a part thereof, wherein the figure is a perspective view of the circus toy.

What I claim is:

The ornamental design for a circus toy, as shown.

LOUIS MARX.
